UNITED STATES PATENT OFFICE.

JOHN S. LYON, OF ROCHESTER, NEW YORK, ASSIGNOR TO JOHN BARTHOLOMEW, OF ROCHESTER, NEW YORK.

COMPACT-POWDER HOLDER.

Application filed April 26, 1923. Serial No. 634,662.

To all whom it may concern:

Be it known that I, JOHN S. LYON, a citizen of the United States, residing at Rochester, in the county of Monroe and State of New York, have invented certain new and useful Improvements in Compact-Powder Holders; and I do hereby declare the following to be a full, clear, and exact description of the same, reference being had to the accompanying drawings, forming a part of this specification, and to the reference numerals marked thereon.

My present invention relates to toilet requisites and more particularly to containers or holders for face powder. Such powder is now largely sold in compressed cakes contained in suitable boxes and supported therein in a metallic holder that prevents it from cracking or chipping and at the same time constitutes a refill for the box or vanity case when desired. The invention has for its object to provide an improved holder that may be cheaply produced and which will be light and serviceable though strong and sufficiently unyielding to protect the powder cake. To these and other ends the invention resides in certain improvements and combinations of parts all as will be hereinafter more fully described, the novel features being pointed out in the claims at the end of the specification.

In the drawings:

Figure 1 is a central vertical section through a powder box containing a cake and holder constructed in accordance with and illustrating one embodiment of my invention.

Figure 2 is an enlarged vertical section through the powder holder and cake;

Figure 3 is a bottom view of the powder holder and

Figure 4 is a top view thereof before it is filled.

Similar reference numerals throughout the several views indicate the same parts.

Referring first to Figure 1, 1 indicates the body and 2, the lid of common form of powder box having a cylindrical lining wall 3 over which the flanges of the lid engage. Within the box is a dome shaped powder cake 4 within a metallic holder indicated generally at 5.

The holder consists of a shallow dish or tray embodying a bottom 6 and a flanged rim 7 and as before stated this must be light in weight so that it is stamped from thin sheet metal. The powder is compacted into the holder under pressure by suitable filling machinery in an effort to cause it to cling so intimately to the surfaces of the holder that it will adhere thereto. However, a difficulty has been experienced in that the pressure exerted on the holder in filling tends to cause the side walls or flanges 7 to spring or give outwardly under the lateral pressure of the powder. This, in turn, causes the bottom 6 to bulge upwardly so that while the cake 4 is in actual process of being molded it is molded to a tray or holder that is in distorted condition. Thus when the pressure is relieved the slightly convex bottom 6 to which the cake has been shaped recedes to a normal flat condition and draws away from an intimate supporting contact with the powder making loosening and breakage probable if not inevitable.

To overcome these difficulties I have devised a very simple expedient which I find to be effective and which adds nothing to the cost of production. It consists in punching an annular groove 8 in the bottom 6 of the holder closely adjacent to the flange or side wall 7 and which forms the corresponding annular rib on the inside of the holder. The effect of this is twofold: in the first place the crimping of the metal has the well known effect of hardening it so that it is less flexible and gives less tendency to the wall 7 to spread and in the second place it strengthens the bottom of the holder in the region where the relative movement of the flange and bottom is transmitted from one to the other.

I find in practice that the provision described is most effective and the powder cake and holder are accurately fitted to each other during the molding operation.

I claim as my invention:

1. A tray or holder for compacted powder cakes embodying a sheet metal bottom having a surrounding shallow flange providing an upright side wall, the bottom being provided with an annular rib punched

up from the under side thereof and closely adjacent and parallel to the base of said side wall.

2. The combination with a tray or holder 5 embodying a sheet metal bottom having a surrounding shallow flange providing an upright side wall, said bottom being provided

with an annular rib punched up from the under side thereof closely adjacent and parallel to the base of the side wall, of a cake 10 of compressed powder molded into said tray in intimate contact with all of the walls thereof.

JOHN S. LYON.
